(57) **CLAIM**

The ornamental design for a set of cabinets, as shown and described.

DESCRIPTION

FIG. 1 is a perspective view of a first cabinet of a set of cabinets, isolated for clarity of disclosure;

FIG. 2 is another perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is a perspective view of a second cabinet of the set of cabinets, isolated for clarity of disclosure;

FIG. 10 is another perspective view thereof;

FIG. 11 is a left side elevational view thereof;

FIG. 12 is a right side elevational view thereof;

FIG. 13 is a rear elevational view thereof;

FIG. 14 is a front elevational view thereof;

FIG. 15 is a top plan view thereof;

FIG. 16 is a bottom plan view thereof; and,

FIG. 17 is a left side elevation view of the set of cabinets, showing my new design.

The broken lines present in the drawings illustrate portions of the set of cabinets that form no part of the claimed design.

1 Claim, 17 Drawing Sheets
